BARBED WIRE

Harold Athelstane Abbott, Bendigo, Victoria,
AustraliaApplication December 20, 1939, Serial No. 310,257
In Australia February 13, 1939

4 Claims. (Cl. 256—7)

This invention has reference to a method of and means for manufacturing barbed wire and the like and has been devised to provide a method comparatively cheap to carry out and is particularly applicable for manufacturing a high tensile, single strand barbed wire.

Hitherto attempts to make a single strand barbed wire using high tensile material have failed owing to the hardness and brittleness of the wire. Electrical welding of the barbs to the wire has been tried and this has not been successful owing to the high carbon content of the wire, for when welding takes place the heat applied to the wire destroys its characteristics causing the wire to become very brittle which wire will snap when a slight bending strain is placed thereon.

It was realised that if a single strand high tensile wire could be utilized as a main wire and have barbs securely locked thereon in spaced relationship a great advantage could be obtained as a much cheaper and stronger barbed wire could be produced, for example, from one cwt. of 12½ gauge high tensile wire a length of approximately 1,500 yards could be produced, the breaking strain of said wire being 1,250 lbs., whereas from one cwt. of 10 gauge soft wire (normally employed), a length of approximately 854 yards only could be produced, the breaking strain of the latter wire being 1,008 lbs.

The main object of the present invention therefore is to provide a method of and means for manufacturing a single strand barbed wire using a high tensile main wire and barbs made from either high tensile or soft wire.

With the above object in view the present invention consists in constructing a single strand barbed wire from a high tensile wire without the application of heat, the barbs being wound around and locked to the main wire in such a manner as to prevent their rotational or longitudinal movement on said main wire.

The invention is characterized by the employment of a single strand high tensile wire having spaced kinks or spaced sets of adjacently opposed kinks formed therein, the said kinks being adapted to receive and retain in determined and intimately locked position respective barbs of high tensile or soft wire, the said barbs being wound preferably in opposite directions around the single strand wire to obtain a uniformly barbed wire, the complete operation being carried out without the application of any heat to the main wire or barbs, means being provided for

forming the kinks in the main wire and means for attaching the barbs in position.

An important feature embodied in my invention is the employment of specially formed kinks in the main wire for receiving respective barbs which, by their action of being wound around the main wire, locks said barbs in determined position.

Another important feature embodied in my invention is the manner in and means by which the kinks are formed in the high tensile main wire so as not to destroy its properties and characteristics, and thereby reduce the breaking strain of the said wire.

15 A further important feature embodied in the invention is the utilisation of a single strand high tensile wire having sets of barbs dispersed and locked in spaced relationship thereon, means being provided for carrying out the complete 20 operation.

The machine for attaching the barbs to the main wire may be carried out according to known engineering practice and therefore no particular machine is herein described or illustrated. 25 However, the manner in which the kinks are formed in the main wire is important since the operation must be carried out without damage to the properties or characteristics of the main high tensile wire and one form of carrying out 30 the operation is described and diagrammatically illustrated.

In order that the invention may be more readily understood reference will now be made to the accompanying drawing which illustrates the 35 formation of the kinks in the main wire and the steps in the cycle of attaching the barbs to said wire and in which drawing:

Fig. 1 is an elevation of portion of the main strand showing adjacent and opposed kinks formed therein.

Fig. 2 is an elevation of portion of the main strand with the barbs in the first operative position.

Fig. 3 is an underside plan of Fig. 2.

45 Fig. 4 is a plan view of portion of the main strand showing the barbs bent from their position as shown in Fig. 3.

Fig. 5 is an elevation of Fig. 4.

Fig. 6 is an elevation of portion of the main 50 strand showing a further step of bending the barbs from their position shown in Fig. 5.

Fig. 7 is an elevation of portion of the main strand showing the barbs twisted and locked into the final position.

55 Fig. 8 is a diagrammatic view of a pair of co-

acting rollers for forming the kinks in the main strand.

Fig. 9 is a diagrammatic view of the forming rollers in operative position after forming adjacently opposed kinks in the main strand.

Fig. 10 is a sectional elevation on line 10—10 of Fig. 9 and illustrating a plurality of main strands passing between the co-acting rollers.

Fig. 11 is an elevation of a modified construction of the main strand illustrating the employment of a single kink for locking the barbs in position.

According to one form of carrying the invention into practical effect the barbed wire consists in a single strand high tensile wire 12 having sets of adjacently opposed kinks 13 and 14 formed in spaced relationship therein by any suitable means such as co-acting rollers 15, the said kinks being preferably of a substantially semi-circular formation and adapted to receive and maintain in determined and locked position respective barbs 16 and 17, of high tensile or soft wire.

The barbs 16 and 17 are wound preferably in opposite directions around the single strand wire 12 to thereby lock the said barbs 16 and 17 and obtain a uniformly barbed wire having a desired number of barbs protruding in pre-determined directions, the complete operation of working the wire 12 and mounting the barbs being carried out without the application of heat, which would destroy the characteristics of the high tensile wire.

In operation a single strand or a plurality of single strands of high tensile wire 12 is or are fed through suitable rollers 15 in order that sets of adjacent and opposed kinks 13 and 14 are formed in said wire 12 the said sets of kinks 13 and 14 being spaced along the wire 12 according to the distance required between the sets of barbs 16 and 17.

The kinks 13 and 14 are of a semi-circular construction, having a desired radius and off-set sufficiently to receive and have locked therein respective short lengths of wire which form the barbs 16 and 17.

The formation of the kinks 13 and 14, and the manner in which such formation is carried out, is important as the properties and characteristics of the wire 12 must not be damaged or affected. For example, I have found that by forming the kinks 13 and 14 with dies in conjunction with a press (not shown) the tensile strength of the wire 12 was greatly reduced and thereby the value of utilizing a high tensile wire was more or less nullified.

Experiments proved that by employing co-acting rollers 15 provided with means herein-after described for correctly forming the kinks 13 and 14 by a rolling operation and using lubrication on the wire 12, the tensile strength of the said wire 12 was not substantially reduced, the slight reduction being overcome by employing a larger radius at the points 18, namely where the respective ends of the kinks 13 and 14 join the straight portion of the strand 12.

While the preferred form of forming the kinks 13 and 14 is by means of co-acting rollers, any suitable means according to known engineering practice may be employed for the purpose providing the tensile strength of the wire is not substantially reduced.

The co-acting rollers 15 are each identical in formation and each comprises a cam-like member most of the periphery of which forms the circumference of a circle, the remaining portion

of the periphery being irregular and comprising curved projections 19 and 20 and indentations 21 and 22 (see Figures 8 and 9) in order to form adjacently opposed sets of kinks 13 and 14 at spaced relationship along the wire or wires 12 when same is or are passed between the said co-acting rollers 15 which rollers 15 are rotating during the operation, so that the respective projections 19 of each roller 15 co-act with the respective indentations 21 of the said rollers 15 and the projections 20 with the indentations 22.

The co-acting rollers are suitably spaced apart according to the gauge of the wire 12 being employed and any well known means is provided for lubricating the wire 12 before, and if desired, while passing between the kink forming rollers 15, such lubrication assisting in preventing any reduction in the tensile strength of the wire 12 due to the kink forming operation.

In operation, the projections 19 and indentations 21 form the adjacently opposed kinks 13 and 14 while the projections 20 and indentations 22 impart the correct curve at the respective points 18, namely where the end of each kink 13 and 14 joins the straight portion of the wire 12. Besides forming the correct curve the projections 20 and indentations 22 maintain the wire 13 in continued alignment although suitable guides (not shown) may be employed for the purpose.

After the operation of forming the kinks 13 and 14 in the main strand 12 the said strand moves forward to permit two lengths of barb forming wires 16 and 17 to be fed through the respective kinks 13 and 14 and cut to a required length by suitable means on the feeding machine which cutting operation points the barbs, such operation as shown in Figures 2 and 3 being the first in the cycle of operation for mounting the barbs 16 and 17 to the main strand 12.

In the next or second operation, the cut pieces of barb forming wires 16 and 17 are bent over one another by suitable means to a U or hairpin shape (see Figures 4 and 5), the legs of each U-shaped wire 16 and 17 being parallel to the main strand 12, the looped end of each wire 16 and 17 being disposed within their respective kinks 13 and 14.

The third operation consists in bending portion of the respective legs of each barb-forming wire 16 and 17 to a vertical position only one up and one down as shown in Fig. 6 so as an H-like construction is formed by the two barb pieces 16 and 17, the respective up-turned and down-turned portion of each barb piece 16 and 17 being on opposite sides of the main strand 12.

The next and final operation consists in twisting the vertical portions of each barb piece 16 and 17 in opposite directions around the longitudinal main wire 12 as illustrated in Figure 7 to thereby lock the barbs 16 and 17 in position and so obtain in this instance a four pointed barbed wire having a barb projecting at each 90 degrees around the wire 12.

To obtain such disposition of the barbs 16 and 17 it is necessary that one barb piece 17 must be given a half turn more than the other barb piece 16.

While it is preferable to employ adjacently opposed kinks 13 and 14 in the main strand 12, the invention is not limited to such formation and in a modification as illustrated in Figure 11, I provide a main strand 23 having a single kink 24 within which is disposed the looped end of one 70 of the barbs 25, the looped end of the other barb

26 being disposed over the kink 24 and under the barb 25, the operation of bending and twisting to the barbs 25 and 26 into position being similar to that previously described.

Although the invention has been described with reference to the manufacture of barbed wire from high tensile wire, I would have it understood that barbed wire made from soft wire may be similarly constructed, as barbed wire constructed in the manner herein described possesses many advantages over existing barbed wires. For example, the barbs under the present invention are effectively locked and set in determined position during manufacture and more so when a tension is placed on the main single strand 12.

It will also be understood that the method of mounting the barbs is not limited to barbed wire and may be employed in the construction of wire mesh fencing, and I do not wish to be arbitrarily confined to the hereinbefore mentioned details since I may if necessary depart therefrom and while I have described the essential characteristics of my invention I desire it to be understood that various improvements and modifications may be embodied therein without departing from its spirit and scope.

I claim:

1. A barbed wire construction comprising, a single strand main wire, spaced pairs of oppositely disposed kinks in said main wire, a pair of barb forming wires associated with each pair of kinks, a U-shaped section in each said barb forming wire arranged with the bend thereof in one of said kinks, the limbs of the U-shaped section of each pair of barb forming wires overlapping and extending in opposite directions in parallel alignment with said main wire, and parts of each barb forming wire contiguous to the limbs of the U-shaped section thereof being twisted in the same direction around said main wire and projecting therefrom to constitute two barbs, and the respective wires of each pair of barb forming wires being oppositely twisted around the main wire.

5 2. A barbed wire construction comprising, a single strand main wire, spaced pairs of kinks in said main wire, each said pair of kinks comprising two oppositely disposed contiguous bends, a pair of barb forming wires associated with each pair of kinks, a U-shaped section in each said barb forming wire arranged with the bend thereof in one of said kinks, the limbs of the two U-shaped sections of each pair of barb forming wires overlapping and extending in opposite directions in contact with each other and in parallel alignment with said main wire, parts of each barb forming wire contiguous to the limbs of the U-shaped section thereof being twisted in the same direction around said main wire, the respective wires of each pair of barb forming wires being twisted in the opposite direction around the said main wire, and the ends of each said pair of wires forming four barbs disposed at an angle of 90° relatively to each other.

10 3. A barbed wire construction comprising a single strand main wire having a kinked part, a pair of barb forming wires, each having a U-shaped bend therein, the bends in the respective barb forming wires overlapping one another and being oppositely disposed, each said bend straddling the kinked part of said main wire, the parts of each said barb forming wire contiguous to the bend therein being coiled around an unknotted part of said main wire adjacent to the kinked part thereof, and the ends of each barb forming wire projecting from the main wire to constitute two barbs.

15 4. A barbed wire construction as claimed in claim 3, wherein the two parts of one barb forming wire contiguous to the bend therein are coiled around the main wire in one direction, and the corresponding parts of the other barb forming wire are coiled around the main wire in the opposite direction.

HAROLD ATHELSTANE ABBOTT.
